(57) **CLAIM**

The ornamental design for a bottle, as shown and described.

DESCRIPTION

FIG. 1 is an elevational front view of the bottle, with
elevational rear and side views being identical due to axial
symmetry, in accordance with the design;

FIG. 2 is a top view of the bottle of FIG. 1;

FIG. 3 is a bottom view of the bottle of FIG. 1;

FIG. 4 is an elevational front view of the bottle of FIG. 1
with cap removed, with elevational rear and side views
being identical due to axial symmetry;

FIG. 5 is a top view of the bottle of FIG. 1 with cap removed;
FIG. 6 is a top view of the cap for the bottle of FIG. 1 in
isolation;

FIG. 7 is an elevational front view of the cap of FIG. 6, with
elevational rear and side views being identical due to axial
symmetry; and,

FIG. 8 is a bottom view of the cap of FIG. 6.

1 Claim, 5 Drawing Sheets
